ATHLETIC SHIRT AND METHOD OF MAKING
THE SAMESamuel N. Friedland, Rochester, N. Y., assignor to
Champion Knitwear Company, Inc., Rochester,
N. Y.

Application January 20, 1938, Serial No. 185,984

4 Claims. (Cl. 2—113)

This invention relates to improvements in the method of making garments generally, and the provision of a garment construction more particularly designed for use in athletics and popularly known as sweat shirts and jerseys.

Heretofore it has been the general practice in various methods of manufacturing the conventional sweat shirt or jersey to make the same of at least four pieces, namely, the front and back pieces comprising the body and a separate piece for each sleeve. In the fabrication of the well known slip-on or slip-over type of athletic shirt, the body is generally formed of the front and back pieces which are sewed together in seams extending across the shoulders and along the two sides to which are stitched the separate sleeves by further seams. Thus, such garment constructions require a number of seams which are disposed not only along the shoulders of the garment but also at the arm pits and the other points at which the sleeves are attached to the body. It is well known that due to the continuous movement of the arms of the wearer, the greatest strain in the use of any such garment takes place in the seams in and around the arm pits and shoulders, and under such strain, the seams naturally tend to split and come apart all too readily, not only causing the garment to lose its shape, but also limiting its period of usefulness by reason of the inevitable rips, tears and the like, which result. In order to overcome this tendency of the seams to split, various constructions such as special seam structures and reinforced stitching have been resorted to, but even with any such arrangement, the garments heretofore available to the trade have been inadequate and objectionable in that, under continuous, every day use, the period of worthwhile service is less than a few weeks of a season, which of course works a hardship on athletic organizations having limited funds for equipment.

It is therefore a primary object of this invention to provide a sweat shirt or jersey construction which overcomes all the insufficiencies of the prior art structures and comprises an exceptionally strong and durable garment, inexpensively and simply manufactured from a single, integral piece of fabric (trimmings such as collars, cuffs, etc. excepted) and requiring only a minimum number of seams which are substantially unexposed and so positioned at the points of greatest strain that the completed garment is capable of withstanding rips, tears and splitting of the

seams as a result of heavy wear and rough usage which takes place in the more strenuous sports.

In forming sweat shirts and jerseys it has also been the conventional practice to make the body piece with the wales or ribs running lengthwise 5 therein so that the maximum stretch occurs about the body. This, of course, is adequate for stretching in that portion of the body which lies below the arm and shoulders, but it has been found that this arrangement does not provide for 10 sufficient stretching in and around the shoulders as required in a number of important uses of such garments. For example, in the sport of football, it is well known that the players are equipped with shoulder pads which are worn 15 underneath the sweat shirt or jersey. These shoulder pads are usually quite bulky and when it is necessary to wear a sweat shirt or jersey over such shoulder pads, there is little provision 20 for the necessary added stretching which is required in the garment. This condition necessarily results in discomfort to the wearer and, quite often, so retards freedom of movement in 25 the arms and shoulders as to cause a detrimental effect on the playing ability of the individual. And this objectionable binding about the shoulders and arms is particularly evident when a garment is worn after laundering when it naturally shrinks to a size smaller than its initial character.

It is therefore a further primary object of this invention to produce a sweat shirt or jersey construction in which that portion of the garment comprising the shoulders and arm pits is capable of any reasonable stretching requirement and in 35 which the stretching taking place in the body portion is such as to permit the garment to conform snugly to the body of the wearer. In carrying out this object, this invention contemplates the provision of a sweat shirt or jersey construction in which the knitted courses, ribs, or wales 40 of the fabric are disposed substantially horizontally throughout the completed form of shirt including the shoulders and sleeves, together with enlarged arm pit portions whereby the garment 45 is capable of any required stretching in and around the shoulders thus providing for maximum comfort and freedom of movement of the wearer either with or without auxiliary equipment such as shoulder pads, and the like.

A further object of the invention contemplates the provision of a method for making a sweat shirt, jersey or the like in an unusually inexpensive and expeditious manner and in which the garment produced is most comfortable and serv- 50 55

iceable to the wearer, unusually durable, and is extremely simple in construction facilitating manufacture thereof and otherwise reducing the costs of production of such garments to a minimum.

5 A still further object of the invention is for the provision of a garment formed in a one piece body and sleeve arrangement in which the wales or knitted courses are disposed substantially horizontally throughout and comprises 10 seamless shoulders and enlarged arm pits suitably designed to provide for any necessary stretching therein together with the shoulder portions, and lengthwise of the body portion thereof 15 to conform snugly to the body of the wearer.

With the above and other objects in view, the present invention has for a more specific object the method of making an entire sweat shirt or jersey, trimmings excepted, of an integral piece 20 of tubular material, with the wales or ribs disposed substantially horizontally throughout in a procedure consisting of alternately reverse cuttings of the garment pattern whereby substantially the entire tube is utilized with very little waste, and 25 with the body of the garment blank thus formed from the tube provided in its initial desired configuration together with all other parts of the garment including the sleeves, also provided from the tube without destroying the character of the 30 fabric of which the garment is formed.

Further objects and advantages of the invention will be apparent to those skilled in the art as a description thereof proceeds with reference to the accompanying drawing showing a preferred embodiment now in extensive use and which has 35 been found in practice to give most satisfactory and reliable results.

Fig. 1 represents a section of tubular knitted fabric with the ribs or knitted courses thereof 40 running longitudinally and illustrating in general, the method of cutting the desired garment patterns from a minimum of material in alternately reverse blanks such that the wales are disposed substantially horizontally throughout in the one 45 piece sleeve and body members thus obtained;

Figs. 2, 4 and 5 indicate the several steps in the method for completing the improved garment construction, Fig. 2 illustrating, on an enlarged scale, a garment blank obtained by the cutting 50 operation of Fig. 1 with the lower edge thereof suitably slit to provide the necessary body opening;

Fig. 3 is a section taken on line 3—3 of Fig. 2 looking in the direction of the arrows and showing 55 the blank as slit along the lower edge portion thereof in providing the body opening;

Fig. 4 indicates the step in the method by which the garment is stitched in single continuous seams, represented by dotted lines, to complete the sleeves 60 and body portion;

Fig. 5 illustrates the final step in finishing the garment comprising the application of sleeve cuffs, waistband and neckband or collar; and,

Fig. 6 is a front view of a completed sweat shirt 65 made in accordance with the invention and is intended to illustrate the advantageous stretching characteristics of the improved garment by reason of the horizontal wale construction and enlarged arm pit portions providing for greater freedom of 70 movement in and around the shoulders and arms, with the body portion thereof conforming closely to the body of the wearer.

In any garment of the class described intended 75 for use, more particularly, in athletics and training quarters, it is well known that satisfactory

service conditions require that the garment shall not encumber the wearer in the least and should permit perfect freedom of movement of the arms, shoulders and head. However, in providing for such freedom of movement, it is also absolutely 5 essential that the garment snugly fit the body of the wearer not only from the standpoint of appearance, but also because of the fact that loose hanging body portions become a nuisance resulting in extreme discomfort and annoyance to the 10 wearer and otherwise present a means which may possibly become entangled with the arms or legs of another player in close quarters causing possible injury. Another example of this disadvantage is seen in the sport of football where it is 15 quite obvious that a loose hanging body portion on a jersey worn by a player running with the ball, affords an unnecessary advantage to an opponent who, of course, is privileged to grasp and clutch such loose hanging body portion to halt the runner, and this naturally requires considerably less skill and ability than the more usual, necessary method of tackling with the arms and shoulders.

Referring to the accompanying drawing in which like reference characters designate like 25 parts throughout the several views thereof, it will be understood from an inspection of Fig. 1, that in the method of making a garment in accordance with the present invention, a tube 10 of knitted fabric is provided having its knitted courses, ribs 30 or wales extending lengthwise thereof, as shown. The diameter of the tube is such as to more or less approximate the desired distance from the waist to the neck and shoulders in any selected size garment; and due to the elasticity of the fabric 35 any diameter of tubular material will be satisfactory for the construction of several sizes of garments, so that an entire group of sizes may be made up by comparatively few cutting appliances and other manufacturing apparatus. The tube 40 of material thus provided is then cut generally transversely in a suitable pattern comprising alternately reverse garment outlines so arranged that the sleeve portion of a blank is obtained from the material adjacent the body portion of the next 45 succeeding blank. Accordingly, by arranging the cutting of the material in opposite overlapping or dovetailing relation, the garment blanks, each including both the body and sleeves of the garment, may be formed in an integral piece of fabric 50 with very little wastage of material and therefore from a minimum of material with the wales thereof disposed substantially horizontally throughout in every instance.

An essential feature of the garment blank thus 55 obtained is the provision of enlarged arm pit portions by cutting the body and sleeves of each garment along intersecting lines 12, 13, Fig. 1, in what may be termed an obtuse angle forming the desired shape of the garment. As shown, 60 this cutting arrangement results in an intermediate section of material 14 between adjacent garment blanks; this small section of material 14 is the only wastage involved in the instant method and when removed together with cut-out 15 65 forming the neck opening, provides a one piece blank in which the knitted courses or wales are disposed substantially horizontally throughout the body portion and sleeves. And as shown in Figs. 2 and 3, a complete blank 11 thus obtained 70 comprises superposed front and back body portions 20, 21 including sleeves 22, 23 and enlarged arm pit portions 24, 25 formed all in one piece and provided with the neck opening 26.

In the process of completing the garment, the 75

lower edge portion of the body is suitably severed as indicated by the undulated line 21, Fig. 2, and stitched along the side edges 12 of the body and edges 13 at the undersides of the sleeves 5 in continuous seams as indicated by dotted lines 28, 29, Fig. 4. This severing of the lower edge of the body may, of course, be accomplished either before or after the blank is sewed in said seams 28, 29, and since such seams are all that 0 is necessary to complete the sleeves and body portions, it will be appreciated that the process involved is extremely simple, which, of course, facilitates manufacture, and at the same time provides a garment having seamless shoulders 5 which is most important in that the wearing qualities of the garment are considerably increased, it being well known that like garments having separate, inset sleeves are weakest at the 10 points where the sleeves are attached to the body.

The garment blank thus seamed and shaped is accordingly prepared for the finishing operation comprising the application of the trimmings which, as indicated in Fig. 5, may comprise sleeve 5 cuffs 30, waistband 31 and a collar or neckband 32 which may include gussets 33, or the like, providing for the desired amount of give and stretching across the shoulders and otherwise increasing the amount of give of the neck opening to facilitate putting on or taking off of the garment.

While in the illustration of the accompanying drawing separate cuffs are shown, it is to be understood that the presence of such cuffs is a matter of choice and that the present invention 15 is not limited to such construction since a suitable cuff may be provided from an added length on the sleeve which is folded back upon itself and stitched in such folded relation. Likewise, the use of a separate waistband may be dispensed 20 with by providing an added length to the lower edge of the body portion which may be then folded back upon itself and stitched together with pleats, or the like, for suitably shaping and reducing the circumference of the garment in providing for a snug close fit around the body of the 25 wearer.

As previously pointed out, a primary object of the instant invention is the provision of a garment construction in which the knitted courses 30 or wales are disposed substantially horizontally throughout the sleeves and body portion thereof together with especially designed, enlarged arm pit portions 24, 25. As illustrated in Fig. 6, this arrangement permits the desired amount of give 35 and required stretching in and around the shoulders and under the arms from the initial unstretched configuration of the garment, represented in broken lines, to the stretched condition thereof, indicated by the full lines. At the same time, the body portion is readily capable of lengthwise stretching and by the reason of the said horizontal disposition of the wales, has the most desirable tendency of reducing in circumference thereby conforming more snugly to the 40 body of the wearer after a period of use. It will be apparent therefore, that in this construction, a sweat shirt or jersey is especially adapted to give and stretch in the regions where stretching is necessary, such as the armpits and shoulders, 45 and otherwise tends to conform snugly to the body of a user below the shoulders where close fitting is most desirable.

By reason of the said horizontal disposition of the wales throughout in the completed form of shirt, there is a further most important advan-

tage which has been found to make such garments so much more satisfactory and desirable from a practical standpoint of better wearing qualities and characteristics than the more common type of sweat shirts or jerseys, that they 5 have been readily adopted by the trade and are now in extensive use as standard equipment. In washing the ordinary sweat shirt having vertical wales in the body portion thereof, it is well known that due to shrinkage, the garment necessarily becomes much shorter than its original over-all length with the result that the waistband shrinks up to such extent as to be disposed sometimes around the ribs of the wearer and cannot be stretched downward to compensate for 10 such shrinkage and fit properly about the waist of the wearer without causing tightening in the shoulders and arms of the garment and otherwise setting up excessive strain not only in the fibres thereof but also the seams which, of course, 15 too frequently results in objectionable rips, tears and splitting of the seams. In the sweat shirt or jersey construction of the instant invention, however, by reason of the horizontal disposition of the wales throughout the body portion thereof, the garment is capable of ready lengthwise stretching after any number of washing or cleaning operations to the extent that any undesirable, 20 improper fit as a result of shrinkage may be readily overcome, yet the shirt is retained of its 25 original shape and form and otherwise closely and snugly fits the body of the wearer after any such lengthwise stretching as desired or necessary.

It will be also understood that the garment 30 construction of the instant invention is exceptionally strong and durable, is capable of greatly increased wearing qualities and affords a much longer period of service than the more common type of athletic shirt having inset sleeves, these 35 features being the advantageous results necessarily obtained by the complete elimination of seams where the sleeves meet the body portion and the substantially unexposed disposition of the seams along the underside of the sleeves 40 where they are subject to less strain and considerably less damaging wear when used in sports involving bodily contact such as football, lacrosse, 45 ice hockey, etc.

It will be further appreciated that aside from 50 these practical advantages secured in the making of garments in accordance with the invention, there is the further distinct advantage of the greatly enhanced appearance of a garment of 55 this kind which has been found to render the same much more preferred than the ordinary well known form of sweat shirt or jersey.

While the invention has been described in detail with a specific example of the garment construction and the method of making the same, 60 such example is illustrative only, since it will be apparent to those skilled in the art that other modifications within the spirit and scope of the invention may be constructed without departing from the teachings or essential characteristics 65 thereof. The present embodiment is therefore to be considered in all respects as illustrative and not restrictive, the scope of the invention being indicated by the appended claims rather than by the foregoing description, and all changes which 70 come within the meaning and range of equivalency of the claims are therefore intended to be embraced therein.

What is claimed and desired to be secured by the United States Letters Patent, is:

1. The method of making athletic shirts and the like which comprises, providing a length of material in the form of a tube having a diameter approximating the desired over-all dimension 5 from the neck to the waist of a selected size garment, cutting said tube generally transversely in a pattern of alternately reversed garment blanks each comprising integral front and back pieces provided with a neck opening and forming the body and sleeves of the entire garment, severing a garment blank thus obtained along the lower edge of the body portion thereby providing the body opening, and uniting said front and back pieces by seams extending along the sides of the body and undersides of the sleeves. 10
- 15 2. The method of making athletic shirts and the like which comprises, providing a tube of knitted fabric in which the knitted courses run lengthwise thereof, cutting said tube generally transversely in a pattern of alternately reversed 15 garment blanks each comprising front and back pieces forming the body and sleeves in an integral piece of fabric, severing a garment blank thus obtained along the lower edge of the body portion thereby providing the body opening, and 20 uniting said front and back pieces by seams extending along the sides of the body and undersides of the sleeves such that the knitted courses are disposed substantially horizontally throughout the body and sleeves in the completed form 25 of the garment. 30
3. The method of making athletic shirts from tubular material which comprises, providing a tube of knitted fabric in which the knitted courses run lengthwise thereof and which has a diameter approximating the desired over-all dimension 35

from the neck to the waist of a selected size garment, cutting said tube generally transversely in a pattern of alternately reversed garment blanks each comprising integral front and back pieces provided with a neck opening and forming the body and sleeves of the entire garment, severing a garment blank thus obtained along the lower edge of the body portion thereby providing the body opening, and uniting said front and back pieces by seams extending along the sides of the body and undersides of the sleeves such that the knitted courses are disposed substantially horizontally throughout the body and sleeves in the completed form of the garment. 5

4. An athletic shirt of the class described comprising, an integral section of knitted material providing the front and back pieces including the sleeves of the garment, said front and back pieces being provided with a neck opening and formed to include a waist length body portion and tapering sleeves with the wales thereof disposed substantially horizontally throughout the body portion and across the shoulders, said front and back pieces being united by seams at the sides of the body portion and along the undersides of the sleeves, said body portion being relatively small but provided with enlarged arm pit portions which together with said horizontal disposition of the wales thereof provides for ready stretching in and around the shoulders, the horizontal wale 20 construction in the remainder of the body portion causing the same to reduce in circumference on being stretched longitudinally and thereby closely fit the body of the wearer in use. 25

SAMUEL N. FRIEDLAND. 35
